UNITED STATES PATENT OFFICE.

HERMAN VICTOR BAINTS, OF AMSTERDAM, NETHERLANDS.

RAIL-JUNCTION.

1,317,539.

Specification of Letters Patent. Patented Sept. 30, 1919.

Application filed April 16, 1919. Serial No. 290,577.

To all whom it may concern:

Be it known that I, HERMAN VICTOR BAINTS, a subject of the Queen of the Netherlands, residing at Amsterdam, Province 5 of North Holland, in the Kingdom of the Netherlands, have invented certain new and useful Improvements in Rail-Junctions, of which the following is a specification.

The invention relates to an improvement 10 of the junction of the rail-ends and especially of such junctions in which the one rail-end is provided with a projecting part and the counterparting end of the junction-rail has a corresponding recess; both ends 15 are shaped in such manner that a vertical pressure on one of the rail-ends by one or more supporting faces at different elevations is transmitted to the junction rail end.

The invention has the following advantages: The rails in the passage of traffic 20 thereover bend at the joints in an elastic line so that they act similarly to a continuous rail; the rails may be laid or taken up in a very short time with a consequent reduction 25 of cost in the construction of a railroad; and the joints require very little supervision, especially in those cases where the fish-plates commonly employed are dispensed with, since the danger of the rails spreading at the 30 joints is reduced, if not eliminated.

Arched supporting faces are known in rail junctions but not with the above mentioned characteristics. By the arched shape 35 of the supporting face as above indicated, the resistance capacity of the overlapping part is highly increased without harming considerably the solidity of the lapping part.

In view of the construction of the improved rail joint the collection of water is 40 excluded from the adjacent faces or surfaces by reason of the fact that there is an overlap or overhang of one part in respect to the other and as a consequence rust deterioration is prevented.

The application of the invention effectively prevents the lateral sliding of the rail 45 ends with regard to each other, which appears especially at curves in consequence of the pressure of the wheel flanges. It is not 50 so dangerous when the fish bolts work loose in a construction according to the present invention as it would be in previous constructions, where it was disastrous, as a lateral sliding of one of the rail ends is entirely 55 prevented by the invention. In ap-

plying the invention, the vertical pressure can be transferred on one or more arched supporting planes situated on different heights of the rail profile. The accompanying drawings illustrate a mode of embodying the invention. 60

Figures 1 and 2 represent a form of carrying out the invention, in which the upper supporting face, coinciding with the rail-head, is arched while the lower supporting 65 face, being level, is situated at half the height of the railfoot. It may be remarked that also the lower supporting faces may be arched according to the invention.

Figs. 3 and 4 are detail perspective views 70 of portions of rails and embodying a slight modification.

Fig. 5 is a transverse vertical section through the structure shown by Fig. 3 and taken in rear of the reinforcement at opposite sides of the rail. 75

It appears from the drawings, that the rail-ends are constructed in such a manner, that even without fish plates the difference 80 in levels during the using of the rail road is neutralized while a lateral sliding of the rail ends is prevented by a special form of the supporting faces.

Any kind of fish plates may be used at the rail junction according to the invention. 85

The supporting faces may be put at different heights of the rail section; both rail ends should remain sufficiently strong lest deformation may appear.

The supporting face transmitting the 90 vertical pressure from one rail end to the other is represented in the drawing by *a*, *b* is the corresponding supporting face of the junction rail taking up the pressure, and *c* is the end face of the rail. The end face 95 of the projecting part of the one rail is indicated with *d*, while the end surface of the corresponding recess in the junction rail is represented by *e*.

The arch of the curved supporting face 100 is preferably elliptical. In the drawing the vertical section represents an ellipse with the longitudinal axis passing through the lower part of the head.

The supporting faces of the rails should 105 not exceed a certain length, a desirable length being from 3.5 centimeters to 5 centimeters.

If the end faces make an angle with a vertical plane, which is perpendicular to the 110

direction of the rail (which is advantageous), this angle may be preferably not greater than 30° .

The invention may be used with the same advantage with double headed English rails and with grooved rails as it gives in using the usual rails.

The Figs. 3, 4 and 5 illustrate the invention applied to rails with reinforced profile, 10 in the joints.

What I claim is:

1. A rail joint having the head of one rail cut vertically at a distance from the free end to form a square abutting shoulder the full 15 extent across the head and intersected by a horizontal convex support continuing fully to the rail end and of less width than the head, and an adjacent rail having a straight head end with a concave recess cut into and 20 solely under the thread surface of the head to receive and fully inclose the horizontal convex support of the first named rail end with the said straight head end abutting against the said shoulder; the remaining web 25 and base flange portions of the rail ends

having a snug fitting coöperating construction.

2. A rail joint having the head of one rail cut vertically at a distance from the free end to form a square abutting shoulder the full 30 extent across the head and intersected by a horizontal convex support continuing fully to the rail end and of less width than the head and also having the base flange horizontally undercut and transversely reduced 35 by square side shoulders and a projecting vertical web, and an adjacent rail having a straight head end with a concave recess cut into and solely under the thread surface of the head and the web also cut away vertically and the base recessed above the lower side to snugly receive the support, projecting web and undercut side shouldered portions of the first mentioned rail end.

In testimony whereof I have hereunto set 45 my hand.

HERMAN VICTOR BAINTS.
